Jacob G. Binder
BY James N. Ramsey

ATTORNEY

UNITED STATES PATENT OFFICE.

JACOB G. BINDER, OF BROMLEY, KENTUCKY.

SINK-DRAIN STOP.

Application filed March 4, 1924. Serial No. 690,903.

To all whom it may concern:

Be it known that I, JACOB G. BINDER, a citizen of the United States, residing at Bromley, in the county of Kenton and State 5 of Kentucky, have invented certain new and useful Improvements in Sink-Drain Stops, of which the following is a specification.

My invention relates to improvements in water stops for sinks, bath tubs and the 10 like.

The objects of my invention are to provide a water stop, having its top flush with the sink bottom or other article in which it is embodied thereby keeping the sink bottom 15 free from obstacles and avoiding unintentional release of the stopper; to provide means to retain the stopper in an elevated position adapted to admit the flow of water from the sink into the usual drain pipe, said 20 means comprising mechanism controlled by a manually operative stem connected to the stopper whereby said stopper may be rotated a part turn in one direction for retaining said stopper in an elevated position and a 25 part turn in the opposite direction for permitting said stopper to be lowered for stopping the flow of water from the sink into said drain pipe.

Another object is to provide a water stop 30 having means for retaining the stopper in desired position without the use of springs.

My invention consists in providing a vertical fin extending longitudinally of a stem connecting a stopper and a strainer; in providing a slot adapted to receive said fin whereby when the manual operative means connected to the strainer of my water stop is elevated, said stem and stopper are raised therewith and when said stopper is positioned at a predetermined point, said manual operative means may be rotated a part turn, whereby the lower end of said fin is adapted to engage a portion of the water stop and remain in fixed position relative to 40 downward movement thereby permitting the water to flow from the sink into the usual drain pipe and when it is desired to close the outlet leading into said drain pipe said manual operative means may be rotated in an

opposite direction whereby said fin enters 50 said slot thereby permitting said stopper to be lowered into engagement with its seat.

My invention also consists in the details of construction and in the parts and combination and arrangement of parts as herein 55 set forth and claimed.

In the drawings:

Fig. 1 is a top view of my sink stop;

Fig. 2 is a section of the same taken on a line corresponding to 2—2 of Fig. 1 showing the lower end of the drain pipe broken away and the method of connecting the same to my invention;

Fig. 3 is a side elevation of my improved stopper stem showing my longitudinal fin 65 in side elevation; and

Fig. 4 is a side elevation of my stopper stem showing my longitudinal fin in end elevation;

Fig. 5 is a section of my sink stop showing the stopper in closed position;

Fig. 6 is a section taken on a line corresponding to 7—7 of Fig. 5;

Fig. 7 is a plan view of disk 11;

Fig. 8 is a side elevation thereof; and 75

Fig. 9 is a side elevation of the duct.

In the embodiment of my invention as illustrated and which shows a preferred construction I provide tube 1 received in opening 2 of usual sink bottom 3. The tube is 80 retained against downward movement by flange 4 integral therewith and in engagement with the sink bottom and is retained against upward movement by lock ring nut 5 threaded to the tube and in close engagement with the lower side 6 of sink bottom 3. The lower end of tube 1 is connected to usual drain pipe 7 having flange 8 at its top. The under side of flange 8 is securely engaged by flange 9 of lock ring nut 10 90 threaded to the lower end of tube 1, and is adapted to be tightened for respectively drawing pipe 1 downwardly and drain pipe 7 upwardly in engagement with disk 11 and washer 11' intermediate tube 1 and drain 95 pipe 7. Disk 11 has circular openings 12 therein having flange 13 integral therewith and extending downwardly at an angle

- adapted to provide water tight seat 13' for stopper 14 connected to the lower end of stopper stem 15 by nut 15' threaded to the stem received in hole 16 in web support 17 5 integral with duct 18 having flange 19 fitted in annular groove 20 in the upper end of tube 1 and retained flush with the top of sink bottom 3 by threaded connection 21 with tube 1.
- 10 Stopper 14 is preferably formed of a tubular rubber block 14' having downwardly converging outer walls and rests between a concavo convex metal plate, (threaded to stem 15) and nut 15' threaded on the lower 15 end of said stem.

15 Circular strainer 22 is fixed to the top of stopper stem 15 and is adapted to slidably fit in duct 18. When stopper 14 is in elevated position the top of circular plate is flush 20 with the top of sink bottom 3 as shown in Fig. 2. A plurality of perforations 23 in strainer 22 permits the flow of water and fine waste matter therethrough.

25 Bail 24 has knobs 24' respectively integral with arms 25 respectively extending downwardly through holes 26 in downwardly dished central portion 26 of strainer 22, to permit convenient finger grasping contact with the bail for the purpose of rotating 30 stopper stem 15 and vertically adjusting stopper 14. Duct 18 is screwed into and out of tube 1 by bail 24.

35 Stopper stem 15 has vertical fin 27 integral therewith and extending longitudinally thereof and adapted to be received by slot 28 in web support 17. Semicircular lug 29 integral with the web support has one side registering with one side of slot 28 to prevent stem 27 traveling past the slot when 40 stopper stem 15 is rotated.

45 When it is desired to lower stopper 14 from its position, as shown in Fig. 2, into seating engagement with seat 13' of disk 11 bail 24 is grasped and rotated toward the left thereby through strainer 22 and stopper stem 15 fin 27 is rotated in engagement with lug 29 integral with web support 17. Strainer 22 is then pressed downwardly thereby permitting fin 27 to slide 50 downwardly through slot 28 which permits stopper 14 to be forced into seat 13', as shown in Fig. 5, thereby stopping the flow of water and other materials from the sink into drain pipe 7.

55 When it is desired to open the passage leading from the sink into drain pipe 7, bail 24 is pulled upwardly thereby engaging knobs 24' with the lower side of strainer 22 whereby stopper 14 is elevated from its seat 13'. When the top of strainer 22 is flush with the top of sink bottom 3 the lower edge 30 of fin 27 is designed to be slightly above upper side 31 of web support 17 whereby rotation of bail 24 toward the right causes 65 pin 27 to move from its vertical position

over slot 28 and by engaging the upper side 31 of web support 18 thereby retains stopper 14 in an elevated position and out of engagement with seat 13', as shown in Fig. 2.

I have, therefore, invented a simple, practical, economical and effective device for the purposes intended and which may be attached to articles of various designs and types wherein it is desirable to provide means for stopping the flow of water therefrom without the inconvenience and crude methods employed in supplying a stopper which projects upwardly from the bottom of the sink or other article to which it may be applied. 70 75 80

An advantage of my invention is that the stopper is considerably lower than the level of the sink and it is out of sight and not in the way when washing dishes or using the sink for other purposes and by simple manual operative means the flow of water from the sink into the drain pipe may be stopped or permitted. 85

Another advantage of my invention is that the parts of my invention such as are disclosed may be manufactured from material adapted to withstand the continued effects of water without deterioration and, inasmuch as I employ no resilient means such as usual springs which have heretofore been employed for the purpose of retaining a stopper in a desired position, my invention is not likely to get out of order. Neither does my invention interfere with the flow of water from the sink into the drain pipe as there are no parts adapted to catch waste materials and clog the passage thereof. 90 95 100

While I have shown and described a particular construction and combination and arrangement of parts, it will be understood that my invention is capable of modification without departing from the scope or spirit thereof as defined in the claims. 105

What I claim as new and desire to secure by Letters Patent is:

1. In a sink drain water stop, a sink having a drain outlet, a drain tube in said outlet and having its upper end supported flush with the upper surface of the bottom of the sink, a drain pipe connected to said drain tube and having a valve seat therein, a duct mounted in said tube and having its upper end flush therewith and provided with a downwardly extending web support having a central hole and side slot, a strainer 115 slidable vertically in said duct, a stem connected to said strainer, a stopper connected to said stem and adapted to engage said seat, a vertical fin fixed to said stem and 120 adapted to enter said slot and a stop on said web adapted to engage said fin, substantially as set forth and for the purposes specified. 125

2. In a sink drain stop, a drain tube, a 130

- duct mounted in said tube and having a downwardly extending web support integral therewith, a strainer slideable vertically in said duct, a stem connected to said strainer, 5 a stopper secured to said stem, a seat for said stopper, a vertical fin fixed to said stem and means for engaging said fin for retaining said stopper out of engagement with said seat.
- 10 3. In a sink drain stop, a drain tube, a duct secured in said tube and having a downwardly extending web support integral therewith, a strainer slideable vertically in said duct, a stem connected to said strainer 15 and slideable vertically in said web support, a longitudinal fin integral with said stem, a stopper secured to the lower end of said stem, said web having a slot for receiving said fin to permit vertical movement of said 20 stopper, a drain pipe and manually operative means connected with said strainer adapted to withdraw said fin from said slot and engage said fin with said web for retaining said stopper out of engagement with 25 said seat whereby said drain pipe is opened and permits passage of water from said sink into said drain pipe.
4. In a sink drain stop, a flanged tube having its upper end flush with the sink 30 bottom, a drain pipe connected to the flanged tube, a circular plate intermediate said drain pipe and said flanged tube and having a stopper seat therein, a duct in said flanged tube and having its top flush with 35 said sink bottom, a web support integral with said duct and having a slot therein and having an integral lug extending upwardly, a stopper stem having a perforated disk fixed to its upper end and a stopper fixed to 40 its lower end, said disk slidably received by said duct and said stem slidably received by said web support, a fin integral with said stem and extending longitudinally thereof and adapted to engage said support where- 45 by said stopper is retained in disengagement with said seat, and manual operative means connected with said plate whereby said stem is adapted to be received by said slot for lowering said stopper in engagement with 50 said seat.
5. In a sink drain stop, a flanged tube having its flanged end flush with and connected to the sink bottom, a drain pipe connected to said flanged tube, a disk intermediate said drain pipe and said flanged 55 tube and having a seat therein, a duct in said flanged tube and having its top flush with said sink bottom, a web support integral with said duct and extending downward- 60 ly and having a slot therein and having a lug adjacent thereto, a stopper stem having a perforated circular plate fixed to its upper end and having a stopper fixed to its lower end, said plate slidably received by said 65 duct, said stem slidably received by said 70 web support, a fin integral with said stem and extending outwardly and longitudinally thereof adapted to engage said support whereby said stopper is retained in disengagement with said seat, a manual operative means connected with said circular perforated plate whereby said fin is adapted to slide vertically in said slot for lowering said stopper in engagement with said seat for closing said drain pipe. 75
6. In a sink drain stop, a drain tube, a strainer slideable vertically in said tube, a stem connected to said strainer, a stopper secured to the lower end of said stem, a drain pipe, a seat for said stopper for closing said 80 drain pipe, a fin fixed to said stem and extending outwardly and longitudinally thereof and means for engaging said fin for retaining said stopper out of engagement with said seat. 85
7. In a sink drain stop, a drain tube, a strainer slideable in said tube, a stem connected to said strainer and having a stopper secured thereto, a drain pipe, a seat for said stopper for the purpose of closing said 90 drain pipe, a metal plate or fin fixed to said stem and extending longitudinally thereof and means for engaging said plate for retaining said stopper out of engagement with said seat. 95
8. In a sink drain water stop, a sink having a drain outlet, a drain tube in said drain outlet, a drain pipe connected to said drain tube and having a seat therein, a duct in said tube provided with a downwardly ex- 100 tending web support having a central opening and side slot, a strainer slideable vertically in said duct, a stem connected to said strainer and having a fin thereon adapted to engage said slot, a stopper connected to said stem and comprising a metal disk threaded thereto, a tubular downwardly tapered rubber plug resting against said metal plate, a nut on the lower end of said stem securing said plug to said plate and 105 adapted to engage said seat. 110
9. In a sink drain water stop, a sink having a drain outlet, a detachable tube having its upper end supported flush with the upper surface of the bottom of the sink, a drain 115 pipe, means for connecting said tube to said drain pipe, a duct mounted in said tube and having its upper end flush therewith, a perforated drain plate slidably mounted in said duct and having its upper surface flush with the top of said duct when the drain is open and having the top of said drain plate below the top of said duct when the drain is closed, and means for closing said drain. 120
10. In a sink drain water stop, a sink hav- 125 ing a drain outlet, a tube mounted therein with its top substantially flush with the upper surface of the sink bottom, a drain pipe, means for coupling said tube to said pipe, a duct mounted in said tube with its upper 130

end flush therewith, a supporting web depending from said duct and having a hole centrally therethrough, a perforated vertical slidable drain plate mounted in said duct, a detachable stem depending from said drain plate and having a threaded lower end, said stem extending through said hole

in said web; a stopper secured to said stem below said web, a seat for said stopper in the upper end of said drain pipe, and means for simultaneously moving said drain plate and stopper to upper or open position and to lower or closed position, as desired. ¹⁰

JACOB G. BINDER.
